UNITED STATES PATENT OFFICE.

CHESTER C. LAMB, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

TRAVELING-FLAT CARDING-MACHINE.

1,297,367.

Specification of Letters Patent. Patented Mar. 18, 1919.

Application filed September 6, 1917. Serial No. 189,930.

To all whom it may concern:

Be it known that I, CHESTER C. LAMB, a citizen of the United States, residing at Whitinsville, in the county of Worcester 5 and Commonwealth of Massachusetts, have invented a new and useful Improvement in Traveling-Flat Carding-Machines, of which the following is a specification.

This invention relates to improvements in 10 traveling flat carding machines and more particularly to an improved arrangement for taking up the slack in the flat chains.

In customary construction of traveling flat carding machines the flats are swivelly 15 connected at each end to an endless chain on each side of the machine. In the operation 20 of carding the working flats are supported at their ends on flexible bends concentric with the carding cylinder and slowly move thereon due to motion transmitted by the 25 connecting chains which receive their motion through connections with the cylinder. After passing over the carding cylinder the flats return to their working position over a 30 number of revolving carriers supported in stands fastened to the cylinder arch. After continuous usage the chains become slack due to the wear resulting between the chain 35 link connections. Unless this slackness of the chains is taken up much damage is often 40 done to the clothing on the flats due to the sagging of the line of flats against the adjacent cylinder casings.

The invention consists in the construction, 45 combination, and arrangement of parts and details, as hereinafter described, and pointed out particularly in the claim.

Reference is to be had to the accompanying drawings, forming part of this specification, 50 in which similar numbers of reference indicate corresponding parts in all figures.

Figure 1 is a side elevation of a carding machine in part provided with my improved 55 device for taking up the slack in the flat chain. Fig. 2 is an enlarged side view of the take-up device and its holding stand showing in full and dotted lines the different positions of the carrier supporting the 60 flats. Fig. 3 is an enlarged sectional view 50 on line X Y of Fig. 2 showing the relation of my improved device to the adjacent parts of the carding machine. It is understood 65 that each carding machine has a chain slack 70

take-up device applied on each side of the 55 machine.

In the said figures, 1 is the card side leg, 2 is the cylinder revolving on its shaft 3 in bearing 4 bolted to the card leg. Adjustably mounted on the arch 5 is the flexible 60 bend 6 on the upper surface of which a series of flats 7 connected together by the endless chain slide while in working relation with the clothing on the cylinder. This chain as usually constructed consists of flat 65 steel links swivelly connected together by pins or studs 9 screwed into the ends of the flats thus serving as holders for the same and maintaining them a proper distance apart. 70

After leaving their working position on the cylinder the line of flats is drawn again to their working position by the chain over four carriers 10, 11, 12, and 13 rotating on 75 bearings supported by stand 14, 15, 16 and 17 respectively bolted to the card arch 5.

In course of time, after considerable usage, the chain becomes slack due to wearing of the chain link joints. This results in a sagging in the train of flats especially noticeable at the points of advancing to and leaving the working position on the cylinder. 80

If this slackness is not taken up there is a tendency for the flats to drop away from the end supporting carriers 10 and 13 and 85 thus to be drawn into contact with the edges of the cylinder casings 18 and 19 thus causing considerable damage to the clothing on the flats. It is customary in the present construction of carding machines to employ 90 an adjustable stand for supporting the flat carrier such as the stand supporting the carrier C shown in Fig. 1 of Patent No. 597,314, Jan. 11, 1898. By this construction the take-up of the chain slack is accomplished to a limited extent, when more is required the chain is shortened by removing one or more flats, this procedure necessitating considerable extra work for the operatives and also a loss in the productive 95 capacity of the machine due to the necessary stoppage of the machine. 100

My invention overcomes these disadvantages by making use of the extension stand 20 with two adjusting slots and slidably connected to the bracket 15 bolted to the cylinder arch 5. The circular carrier 11 rotates 105 on the journal 21 integral with the holder

stand 22 which is adjustably and slidably mounted on the stand 20 and is held in a fixed relation thereto by the bolt 23 and nut 24 clamping them together. The position 5 of the carrier can be varied on the extension stand by means of the adjusting slot 25 through which the bolt 23 passes. The extension stand 20 is raised and lowered with reference to the bracket 15 by the adjusting 10 screw 26 and is fixed in any desired position by the bolt 27 passing through the slot 28 and screwing into the boss 29 on the upper part of bracket 15.

In operation of a carding machine when 15 the flat chains are new the flat carrier 11 is set with its holding bolt 23 in the bottom of the extension slot 25 and the adjusting stand 20 is set at its lowest position on the bracket 15 so that the holding screw 27 is 20 at the top of the slot 28. As the chain stretches the operative takes up the slackness by means of the adjusting screw 26 until the full length of the slot 28 is reached, then if further slackness appears in the 25 chain it may be taken up as follows: block up the carrier 11 so that it and the flats supported thereon are maintained in position without depending for support on the

bolt 23 then loosen the bolts 23 and 27 and drop the stand 20 until the top of the slot 30 25 engages with the bolt 23 as shown in dotted lines in Fig. 2. With the stand 20 in this position an additional amount of slackness in the chain may be taken up without the necessity of removing one or more 35 flats as is required in carding machines as at present constructed.

I claim—

In a traveling flat carding machine comprising a driving shaft having a carding cylinder thereon, traveling flats, a chain connecting the traveling flats, power transmitting means between the driving shaft and the chain, a cylinder arch, a flexible bend 40 adjustably mounted on the arch, circular 45 carriers supporting the returning line of flats, supporting stands for the carriers, one of the carriers mounted on a journal integral with a holding stand slidably adjustable on an extension stand, said extension stand 50 being slidably mounted on a bracket fixed to the card arch.

In testimony whereof, I have signed this specification.

CHESTER C. LAMB.
